attorney.

UNITED STATES PATENT OFFICE.

HENRY C. WEEDEN, OF BOSTON, MASSACHUSETTS, ASSIGNOR TO THE WEEDEN SANITARY MANUFACTURING COMPANY, OF RHODE ISLAND.

METHOD OF AUTOMATICALLY FLUSHING BY ELECTRICITY.

SPECIFICATION forming part of Letters Patent No. 416,138, dated November 26, 1889.

Application filed March 18, 1889. Serial No. 303,758. (No model.)

To all whom it may concern:

Be it known that I, HENRY C. WEEDEN, of Boston, in the county of Suffolk and State of Massachusetts, a citizen of the United States, 5 have invented certain new and useful Improvements in Methods of Automatically Flushing by Electricity, of which the following is a specification.

My invention relates to the production of 10 a discharge of flushing-water from a suitable tank having an electrically-operated discharge-valve governing the discharge of water from the said tank or receptacle; and its object is to effect this discharge by means of 15 the liquid poured into the bowl to be flushed when the same is used.

My invention is particularly applicable to 20 that class of bowls—such as urinals and slop-hoppers—in which it is desirable that flushing shall take place automatically and as soon as the bowl is used.

In the accompanying drawing I have represented one form of apparatus by means of 25 which my improved method may be carried out. It is to be understood, however, that, as will hereinafter appear, my improved method is independent of any specific form of apparatus, and is capable of being carried out by other forms of apparatus than that shown; 30 also, that I make no claim herein to any apparatus.

In the drawing I have shown at A a flushing-tank of ordinary construction, the discharge-valve E of which regulates the outflow 35 of liquid through the flushing-pipe F to the bowl G to be flushed. The discharge-valve E is connected to an operating-lever B, which carries an armature C, which armature lies within the field of an electro-magnet D. 40 Such a device as thus far described is a well-known one for the purpose, and has heretofore been operated by means of a push-button or other suitable circuit maker or breaker adapted to be operated by the person using 45 the bowl. Inasmuch as the working of such a push-button may depend entirely upon the volition of the person using the bowl, it is obvious that its use will frequently be omitted

either intentionally or unintentionally. By 50 my improved method, however, I no longer rely directly upon any act of human volition, but employ the fluid introduced into the bowl as a necessary agent and inevitable cause of the production of the flushing action. To do this I employ the fluid introduced into the bowl when in use and passing through or out of the same to effect the electrical energizing of the electro-magnet and thus operate the flushing-valve. This may 55 be conveniently done by locating the terminal at a point within the outward path of the fluid passing from the bowl, so that the fluid as it passes out shall make (or it may be break) the circuit to operate the valve. It is obvious, however, that the method indicated 60 may be followed out with many different forms of apparatus widely differing from each other as well as from the specific form shown.

I am aware that manually producing the 65 operation of a flushing-valve by electricity is old. I am not aware, however, that any one before myself has employed the fluid introduced into the bowl when in use as a substitute for manual energy.

I make no claim here to the apparatus herein shown, as it is the subject-matter of an application for patent which I have filed, Serial No. 300,528.

I claim—
The method of automatically flushing a 70 bowl by liquid normally confined above the same, which consists in pouring other liquid into the bowl and causing the liquid so poured in to make or break an electric circuit controlling a valve, by the movement of which the first-named body of liquid is released from confinement and permitted to descend into the bowl to flush it.

In testimony whereof I have hereunto subscribed my name this 13th day of March, A. D. 1889.

HENRY C. WEEDEN.
